UNITED STATES PATENT OFFICE.

MARY KEY BELL, OF KNOXVILLE, TENNESSEE.

PLUMBING WASTE-PIPE.

No. 861,493.

Specification of Letters Patent.

Patented July 30, 1907.

Application filed June 17, 1904, Serial No. 212,982. Renewed January 23, 1907. Serial No. 353,578.

To all whom it may concern:

Be it known that I, MARY KEY BELL, a citizen of the United States, residing at Knoxville, in the county of Knox and State of Tennessee, have invented a new 5 and useful Improvement in Plumbing Waste-Pipes, of which the following is a specification, reference being had to the accompanying drawing.

My invention relates particularly to waste pipes leading from wash basins and kitchen sinks.

10 The object of the invention is to provide a waste pipe with means for intercepting solid matter passing downward from the basin or sink and to provide means for the convenient removal of such solid matter from the pipe. Such solid matter may consist of mere refuse which 15 should be intercepted to prevent the stoppage of the pipes further down, or it may consist of articles of value, as small articles of jewelry and diamonds and other valuable stones dislodged from their settings.

20 In the accompanying drawings, Figure 1 is a front elevation of a portion of a waste pipe embodying my improvement, the cap to the opening of said pipe having been removed; Fig. 2 is a sectional side elevation looking from the right as shown in Fig. 1; Fig. 3 is a horizontal section on the line, 3—3, of Fig. 2.

25 In said drawings, 1 is the pipe. Its upper end may be joined directly to the basin or sink in the usual manner or said end may be joined to another section of pipe the upper end of which is joined to the sink.

30 At any convenient point below the basin or sink, preferably above the S-form water seal, 2, the intercepting device is located. This consists of a diaphragm, 3, having perforations or openings, 4, sufficiently numerous and large to permit the ready flow of liquid

through said diaphragm and yet small enough to prevent the passage of solid particles of objectionable size. 35 Said diaphragm, of course, is of proper size and shape to completely fill the interior of the pipe. The diaphragm shown in the drawings is made of sheet metal.

Immediately above the diaphragm is located a short 40 horizontal branch pipe, 5, through which access may be had to the space above said diaphragm for the purpose of removing the solid matter lodging thereon. A suitable closing device, 6, is applied to the end of said branch. In the drawings, said closing device is a circular flanged cap interiorly threaded to conform to 45 interior screw threads on the branch pipe. Said closing device may be removed as often as desired; when it is thought that there is an accumulation of refuse or when any article of value has gone down the pipe.

It will be understood that the details of construction 50 may be more or less varied without departing from the principle and spirit of my invention.

I claim as my invention:

As an article of manufacture, a plumbers' trap comprising a one-piece waste pipe of S-form and substantially uniform diameter and having a tubular, horizontal branch located a little above the seal portion of said pipe, a screw-threaded cap closing said branch, and a horizontal, circular, perforated, sheet-metal diaphragm extending entirely across the interior of said pipe and in the same horizontal plane with the lowest portion of said branch, substantially as described. 55 60

In testimony whereof I have signed my name, in presence of two witnesses, this third day of June, in the year one thousand nine hundred and four.

MARY KEY BELL.
